UNITED STATES PATENT OFFICE

EUGENE F. CLARK, OF DAMARISCOTTA, MAINE, ASSIGNOR TO MARSHALL FIELD MILLS CORPORATION, OF PHILADELPHIA, PENNSYLVANIA, A CORPORATION OF PENNSYLVANIA

TUFT YARN FRAME FOR LOOMS FOR WEAVING TUFTED PILE FABRIC

Application filed May 23, 1930. Serial No. 454,950.

This invention relates to improvements in tuft yarn frames for use in looms for weaving tufted pile fabric such as Axminster carpets and rugs.

5 These frames include in their construction a long body bar provided with means on the respective ends thereof for connecting them to and suspending them from the links of endless, parallel, carrying chains which carry 10 a series of frames and pass around sprocket wheels, and which are actuated by the mechanism of the loom to carry the frames successively into and from a yarn delivering position.

15 The means for connecting the frames to and suspending them from the carrying chains comprises at each end of each frame a tongue member rigidly connected to the body bar of the frame and a hook arm movable toward and from the tongue member and having a bill portion on its free end which extends toward the tongue member and which is adapted to engage a chain link to 20 suspend the frame therefrom, the tongue member and the hook arm forming an enclosure which receives the chain link to which 25 they are connected.

The bill portion of the hook arm rests normally in close relation to the tongue member and it is yieldable against spring pressure away from the tongue member for the 30 passage of the chain link between them to permit the application of the tuft yarn frame to and its removal from the link.

35 The bill portion of the hook arm is usually set at such angle to the body portion of the arm from which it projects that the inner or chain engaging surface of the bill portion extends at an acute angle to the body 40 portion.

The foregoing well known means for connecting the tuft yarn frames to the carrying chains therefor has been open to the objection that it sometimes works itself loose and accidentally detaches itself from the carrying chain to which it is connected when it is 45 in service, resulting in much damage to itself and to the loom in which it is used.

50 As the tuft yarn frames traverse the circuit thereof to and from the yarn delivering

position they assume many different angular positions with relation to the carrying chains to which they are connected, as the chains pass over, under and part way around the sprocket wheels which guide and support 55 them and as the frames assume such angular positions with relation to the chain links to which they are connected, the lateral edges of the bill portion of each hook arm, at the respective sides of the inner or chain engaging surface of such portion, sometimes 60 comes into contact with the chain link to which it is connected, one after the other, so that the respective lateral edges or sides of the bill portion will support the frame, one 65 after the other, as the frame is rocked to its different angular positions. This alternate engagement of the respective sides of the bill portion with the chain link causes the bill portion to work its way back or away from 70 the adjacent tongue member until it finally frees itself entirely from the chain link, when the angular positions of the frame are favorable for such operation, and thereby permits the end of the tuft yarn frame supported by it to drop down, as its connecting means thus accidentally detaches itself from the carrying chain. 75

The purpose of my present invention is to overcome the objection herein set forth and I 80 accomplish my purpose by the provision of a connecting means having a hook arm of such novel construction that it will effectually prevent the connecting means from becoming accidentally detached from the carrying 85 chain, as will hereinafter appear.

The invention consists of the elements and the combinations of them hereinafter described and claimed.

In the accompanying drawings illustrating the invention,

Figure 1 is a front view, partly in section, of one end portion of a tuft yarn frame provided with means for connecting it to a carrying chain illustrating one form of embodiment of my invention, including a carrying chain therefor. 95

Figure 2 is a side view of the chain and an end view of the frame.

Figure 3 is a side view, enlarged, of the 100

hook arm of the means for connecting the frame to a carrying chain.

Figure 4 is a section through the bill portion of the hook arm, on line 4—4 of Fig. 3.

5 Referring to the drawings, 2 designates the long body bar of the tuft yarn frame, 3 one end portion of a spool carried by the frame and 5 a row of transversely extending plates forming yarn passages between them 10 for receiving and guiding tuft yarn strands drawn from the spool 3.

The plates 5 which form the yarn strand passages are suitably connected to and project from a longitudinally extending angle bar 6 secured to the bottom of the bar 2. 15 The yarn passages for the strands drawn from the spool 3 may be formed by any of the devices used for this purpose which are well known in this art.

20 The body bar 2 is provided with suitable bearing arms for rotatably supporting the respective ends of the spool 3. A bearing arm 7 is shown in Fig. 1, for supporting the end portion of the spool 3 shown therein.

25 The respective ends of the body bar 2 are provided with oppositely disposed, chain engaging means for connecting them to the carrying chains of the loom, each chain engaging means being of the following construction:

Secured rigidly to the end of the body bar 2 is the lower end portion of a tongue member 8 which extends upwardly from the bar 2 and which is provided with an off-set portion 25 forming an outwardly extending shoulder 9 and which is also provided with a free end portion 10 extending upwardly from the outer end of the shoulder portion 9.

A hook arm 11 is pivotally connected, at 40 12, to the body bar 2 and it extends upwardly from its pivot through and above an opening 13 in the tongue member 8.

The upper end of the hook arm 11 terminates in a bill portion 14 which is inclined 45 downwardly toward and has its free end resting in close proximity to the free end portion 10 of the tongue member 9.

The hook arm 11 is movable on its pivot 12 back from the normal position illustrated 50 in the drawings toward the bearing arm 7; and it is maintained yieldingly in the normal position by a spring 15 which is interposed between a plate 16 adjacent to the bearing arm 7 and the hook arm 11 and 55 against which the hook arm may be moved when it is moved back from its normal position.

The upper portions of the tongue member 11 and the hook arm 8 form an enclosure 17 60 between them for the reception of one of a pair of parallel links 18 and 19 of a carrying chain 20 to which the tuft yarn frame is connected by means of the tongue member 8 and the hook arm 11, in the usual manner. When 65 it is desired to disconnect the frame from the

chain 20, the hook arm 11 is pressed back against the action of the spring 15 until the bill portion 14 of the arm clears the chain link 18 and permits the link to pass out of the enclosure 17, as usual.

70 The lower or chain engaging surface 21 of the bill portion 14 of the hook arm 11 is made bulging or of convex form, transversely thereof as shown in the drawings. The hook arm 11, herein illustrated, is formed of sheet metal and the convex form of the surface 21 is produced by indenting the upper or outer surface 22 the bill portion 14 and thereby bulging the inner or lower surface 21 thereof.

75 The bulging or convex form of the chain engaging surface 21 of the bill portion 14 provides an intermediate bearing surface for engaging the chain link 18 between the lateral edges 23 of bill portion 14 and thereby prevents any direct alternate contact of the edges 23 with the chain link 18, as the tuft yarn frame assumes different angular positions with relation to the chain 20, and, consequently, prevents the bill portion 14 from working, or walking, back from its normal position, against the action of the spring; and, therefore, prevents the tuft yarn frame from becoming accidentally detached from the carrying chain.

80 I claim as my invention:

1. A tuft yarn frame provided with means for connecting it to a carrier chain, said means comprising a chain engaging tongue and a hook arm formed of sheet metal and having a bill portion extending toward the tongue, said portion being concavo-convex in cross section transversely thereof providing a convex chain engaging surface.

2. A hook arm for a tuft yarn frame, 85 formed of sheet metal and comprising a body portion and a bill portion which is concavo-convex in cross section transversely thereof providing a convex chain engaging surface.

90 In testimony whereof I affix my signature.

EUGENE F. CLARK.
